DRAIN CONTROL FIXTURE

Frederick David Chapman, Chicago, Ill., assignor to The Murray Corporation of America, Pittsburgh, Pa., a corporation of Delaware

Filed Jan. 15, 1960, Ser. No. 59,066

Term of patent 14 years

(Cl. D91—3)

FIG. 1

FIG. 2

FIG. 3

FIG. 4

FIGURE 1 is a perspective view showing a drain control fixture embodying my new design;

FIGURE 2 is a front elevational view thereof;

FIGURE 3 is a bottom plan view thereof; and

FIGURE 4 is a side elevational view thereof.

I claim:

The ornamental design for a drain control fixture, as shown.
